[57] ABSTRACT

A carburetor idle control screw, comprising an elongate screw having an inner end received in the idle fuel discharge port of a carburetor and having an outer end extending outwardly of the carburetor into the atmosphere, said screw having an axial passageway therethrough opening thus the inner and outer ends thereof and a radial passageway therein between the ends thereof in communication with the axial passageway and adapted to be placed in registry with the idle fuel supply passage of the carburetor, said inner end of the screw projecting beyond the wall of the throat of the carburetor and into the throat, so that air is drawn into the axial passageway and mixed with fuel from the idle fuel supply passageway and the mixed air and fuel are introduced into the throat of the carburetor spaced from the wall thereof and the fuel is then atomized and thoroughly mixed with air, resulting in less fuel consumption and reduced air pollution.

CARBURETOR IDLE CONTROL MEANS

BACKGROUND OF THE INVENTION

The present invention relates to idle control means for carburetors for internal combustion engines, and more particularly, to an idle control screw for controlling the idle of carburetors for most efficient operation of an engine with which the carburetor is associated under conditions of engine idling and automotive vehicle coasting and deceleration and the like.

When an internal combustion engine is idling or when automotive equipment is decelerating or coasting, the throttle valve of the carburetor is in closed position and fuel is supplied to the engine through the carburetor idle system in bypassing relationship to the throttle valve or throttle plate. The fuel-air mixture supplied to the engine during these conditions is generally too rich and is also wet because of the failure of the air to atomize the fuel properly. Consequently, the fuel is not combusted efficiently by the engine and uneconomical operation of the engine under idling, coasting and decelerating conditions results, with increased fuel consumption and air pollution.

In accordance with the present invention, a unique idle mixture control screw is provided, which introduces air into the fuel before the fuel is supplied to the throttle bore of the carburetor, and the air and fuel are thus premixed, and moreover, the idle screw of the present invention extends substantially into the throttle bore so that the air-fuel mixture is introduced into the throttle bore in spaced relation to the side wall of the carburetor, with the result that the fuel is thoroughly atomized and the air and fuel are effectively intermixed with the result that the engine operates more efficiently and both fuel consumption and air pollution are reduced.

Still further, with the present invention the air-fuel ratio is maintained at a proper relationship even during conditions of idle and the components of the engine accordingly have a longer life.

The results obtained with the present invention, as described briefly above, are not possible with prior art idle mixture screws, the majority of which comprise screws having solid, elongate, conically shaped noses or needle tips which are arranged to seat in the idle discharge port in the carburetor and are adjustable relative thereto to control the amount of fuel passing through the discharge port around the needle on the idle mixture adjusting screw.

Other prior art devices, as exemplified, for example, by U.S. Pat. No. 2,816,573, have air passage means extending through the idle adjusting screws, but these devices still include a conically shaped nose or needle 24 which is arranged to be adjusted relative to a seat 22 to control the flow of fuel from an idle supply passage 18 through the idle discharge port 16 into the throat of the carburetor. Accordingly, the fuel tends to flow downwardly along the wall of the carburetor throat and to adhere thereto and thorough atomization of the fuel and complete intermixing between the air and fuel is not attained.

OBJECT OF THE INVENTION

An object of the invention is to provide a carburetor idle control screw having passage means therethrough for admitting atmospheric air and including further passage means for the introduction of fuel to the inte-

rior of the screw for mixing of the air and fuel, said screw projecting at its inner end into the throat of a carburetor, so that the air-fuel mixture is introduced into the carburetor spaced from the wall thereof for complete atomization of the fuel and thorough intermixing of the air and fuel prior to combustion thereof.

BRIEF DESCRIPTION OF THE DRAWINGS

FIG. 1 is a vertical sectional view through a typical carburetor having the idle adjusting screw of the invention positioned therein.

FIG. 2 is a fragmentary view in section taken along line 2-2 of FIG. 1.

FIG. 3 is a greatly enlarged, fragmentary sectional view of a portion of the carburetor of FIG. 1 with the idle adjusting screw of the invention operatively positioned therein.

FIG. 4 is a still further enlarged, fragmentary sectional view taken along line 4-4 of FIG. 3.

FIG. 5 is a view similar to FIG. 4, with the idle adjusting screw in a different operative position, for restricting the flow of fuel therethrough.

FIG. 6 is an enlarged, perspective view of the idle adjusting screw of the invention.

DETAILED DESCRIPTION OF THE INVENTION

In the drawings, wherein like reference numerals indicate like parts throughout the several views, a carburetor is indicated generally at C and includes an upper portion 10 defining an air horn 11 and a lower portion or body 12 having a throttle bore or carburetor throat 13 therethrough. A venturi 14 is formed in the carburetor between the air horn 11 and throat or throttle bore 13, and a bridge or cross member 15 extends across the interior of the carburetor above the venturi 14 and a main discharge nozzle 16 projects downwardly to the venturi 14. The discharge nozzle 16 is in communication with a float chamber 17 for supply of fuel to the discharge nozzle and thence into the throat or throttle bore of the carburetor under the action of vacuum produced by an engine on which the carburetor is mounted. A float 18 is positioned in the float chamber for controlling a needle valve 19 in a conventional manner to control the supply of fuel F to the float chamber and to maintain the level of fuel in the float chamber at a desired predetermined level. A vent tube 20 extends upwardly from the float chamber 17 and into the air horn 11 of the carburetor for venting the float chamber in a well-known manner.

A main or primary metering jet 21 is fitted in the carburetor at the bottom of the float chamber 17 for metering the rate at which fuel is supplied from the float chamber to the main discharge nozzle 16, and also for controlling the rate at which the fuel is supplied to an idle tube 22 and thence to an idle passage 23 extending through the cross member 15 and downwardly through the wall of the carburetor beyond the venturi 14 and into the area of the throttle bore 13.

The lower end of the idle passage 23 terminates at its lower end in a transversely extending bore 24, having a threaded outer end portion 25 extended through the outside wall of the carburetor and a reduced diameter, cylindrical inner portion or idle discharge port 26 opening into the throttle bore 13 of the carburetor.

A second transverse bore or port 27 extends through the wall of the throttle bore 13 and into the idle passage

23 in upwardly spaced relationship to the discharge port 26.

A throttle valve or plate 28 is pivotally mounted in the throttle bore 13 in a position such that when in its closed position, as shown in FIGS. 1 and 3, the edge of the throttle plate is disposed adjacent the side wall of the throttle bore between the ports 26 and 27 in the idle control circuit.

An elongate idle adjusting screw 29 is threadably adjustably received in the threaded portion 25 of bore 24, and includes a first cylindrical portion 30 disposed in the bore 24 in alignment with the idle supply passage 23, and an elongate, reduced diameter, cylindrical end portion 31 extended through the idle discharge port 26 and into the throttle bore of the carburetor. The screw 29 is externally threaded, as at 32, for cooperation with the threaded portion 25 in the carburetor, and a coil spring 33 is disposed around the outer threaded end portion of the screw 29 for maintaining a predetermined amount of tension on the screw to prevent the screw from accidentally working loose or moving from its set position once adjusted. The outer end of the screw is enlarged and knurled at 34 so that the screw may be manipulated with fingers and a screw slot 35 is also provided in the outer end of the screw for manipulation of the screw with a suitable tool, such as a screwdriver or the like.

An elongate passageway 36 is formed through the center of the screw 29 and opens outwardly through the opposite ends of the screw. A radially extending passageway or port 37 is formed through the side of screw 29 in the midportion 30 thereof, and the radial port or bore 37 has a cross sectional area approximately one-half as great as the cross sectional area of idle supply passage 23. The inner end of passage 36 is diametrically enlarged at 38, and the cross sectional area of portion 38 is the same as the cross sectional area of radial bore or port 37, whereas the outer portion 36 of the axial passageway has a cross sectional area approximately one-half as great as the cross sectional area of inner portion 38.

The length of the inner end portion 31 of screw 29 is such that with the screw adjusted to bring the radial port 37 in registry with the idle supply passage 23, the inner end of portion 31 projects into the throttle bore in spaced relationship to the side wall thereof. Further, as seen in FIGS. 4 and 5, the idle adjustment screw 29 can be adjusted for full flow, as in FIG. 4, with the port 37 axially aligned with the supply passage 23, or for partial or restricted flow, as in FIG. 5, with the port 37 out of alignment with the passage 23.

Thus with the present invention, when the idle screw 29 is properly adjusted, and the throttle plate or valve 28 of the carburetor is closed, air flows inwardly through port 27 and to the supply passage 23 and fuel is supplied through passage 23 to the transverse bore 24, and thence into the radial port 37 of screw 29, whereat the air and fuel are further intermixed with further air flowing inwardly through the passage 36 in the screw 29. The air and fuel are intermixed in the enlarged diameter portion 38 of the screw and are discharged from the inner end thereof into the throttle bore in substantially spaced relation to the wall of the throttle bore, so that the turbulence within the throttle bore effectively atomizes the fuel and thoroughly intermixes the air and fuel, whereby more complete and ef-

ficient combustion takes place with the result that less fuel is consumed and air pollution is reduced.

The idle screw 29 of the present invention may be used with existing, conventional carburetors without requiring modification thereof, and different screws may be provided for use on different types or makes of carburetors.

To use the idle screw of the present invention, the existing, conventional idle screw in the carburetor is removed and the idle screw of the invention is threaded into the opening for the idle screw, with the cylindrical portion 31 of the idle screw slidably extending into and through the idle discharge port 26, rather than seating against the inner end of the port as with conventional idle screws. The fit of portion 31 in the idle discharge port 26 is such as to preclude flow of fuel around the portion 31, and the rate of flow of fuel may thus be accurately regulated by merely orienting radial port 37 relative to passage 23.

As this invention may be embodied in several forms without departing from the spirit or essential characteristics thereof, the present embodiment is, therefore, illustrative and not restrictive, since the scope of the invention is defined by the appended claims rather than by the description preceding them, and all changes that fall within the metes and bounds of the claims or that form their functional as well as conjointly cooperative equivalents are, therefore, intended to be embraced by those claims.

I claim:

1. In a carburetor having a side wall defining an air horn and a throttle bore in communication with the air horn, a throttle valve in the throttle bore for controlling flow of air and fuel therethrough, said side wall having a radial bore therethrough spaced below the throttle valve and including an inner end portion defining an idle fuel discharge port opening into the throttle bore, an idle fuel supply passage means in communication at one end with a fuel supply and in communication at the other end with the radial bore, the improvement comprising an elongate idle mixture control screw extended completely through the radial bore in the side wall of the carburetor and having a screw threaded outer end portion threadably engaged in said radial bore and extending outside the carburetor and having a smooth, cylindrical inner end portion sealingly and slidably engaged in and extended through the idle fuel discharge port and into the throttle bore of the carburetor and precluding flow of fuel through said discharge port around said screw, said screw having an axial passage therethrough opening through the opposite ends thereof and a radial passage communicating at its inner end with the axial passage and at its outer end with the idle fuel supply passage means, so that air is drawn from atmosphere into the axial passage and fuel is drawn through the radial passage into the axial passage and is mixed with air therein, said air-fuel mixture discharged through said inner end of the screw into the throttle bore of the carburetor spaced from the side wall thereof for thorough mixing and atomization of the fuel and air and thus resulting in more efficient operation and reduced fuel consumption and less air pollution.

2. An idle control screw for a carburetor, comprising an elongate externally threaded cylindrical body adapted to extend through the side of a carburetor and having an elongate, cylindrical, inner end portion

adapted to project through an idle fuel discharge port of the carburetor and into a throttle bore portion of the carburetor, said body having an axial passage therethrough opening through the opposite ends thereof and a radial passage through the side thereof in communication at its inner end with the axial passage and adapted to be placed in registry at its outer end with an idle fuel supply passage of the carburetor, so that in use air is drawn in through the axial passage and fuel is drawn in through the radial passage, said air and fuel being premixed in the axial passage and then discharged through the inner end portion into the throttle bore of the carburetor in spaced relation to the wall of the throttle bore for thorough mixing and atomization of the fuel and air and thus resulting in more efficient operation and less fuel consumption and reduced air pollution.

3. The improvement as in claim 1, wherein the axial passage through the screw has a first diameter at the outer end of the screw and a second, larger diameter at the inner end of the screw, said radial passage communicating with said larger diameter, second portion of the axial passage adjacent the juncture of the first and second portions of the axial passage, and said radial

passage has the same diameter as said larger diameter portion.

4. The improvement as in claim 3, wherein the radial passage and said larger diameter portion of the axial passage have a cross-sectional area substantially twice as great as the cross-sectional area of the first portion of the axial passage.

5. The improvement as in claim 4, wherein the radial passage and larger diameter portion of the axial passage have a cross-sectional area substantially one-half as great as the cross-sectional area of the idle fuel supply passage in the carburetor.

6. The improvement as in claim 1, wherein the screw is externally threaded from adjacent the radial passage therein outwardly to said outer end thereof for cooperation with complementary threads in the radial bore in the carburetor, said screw being adjustable to bring the radial passage therein into more or less aligned registry with the carburetor idle fuel supply passage to thus regulate the amount of fuel supplied therethrough.

7. The improvement in claim 6, wherein the cylindrical inner end portion of the screw is of reduced diameter relative to the externally threaded portion thereof.
